Primary Examiner — Mojtaba Tehrani(74) *Attorney, Agent, or Firm* — ALSTON & BIRD LLP(57) **CLAIM**

The ornamental design for a magazine release as shown and described.

DESCRIPTION

FIG. 1 is a perspective view of a magazine release showing the new design;

FIG. 2 is another perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken line in the drawings disclose unclaimed portions of the magazine release only and form no part of the claimed design.

1 Claim, 6 Drawing Sheets(56)
